HOLDER FOR PAINT CANS AND THE LIKE

Marion L. Worthington, Drexel Hill, Pa.

Application July 3, 1947, Serial No. 758,945

10 Claims. (Cl. 15—140.2)

1

This invention relates to supporting devices for receptacles such as paint cans.

Most persons have occasion from time to time to use paint cans of the smaller sizes, e. g. pint and quart cans, which are not provided with handles. The average person has difficulty in handling such a can during use and in preventing the paint from getting onto his hands and on surfaces, such as floors, where the can may be placed. Sometimes the can is accidentally knocked over with consequent serious results. There has long been a need for some simple and inexpensive means to overcome these difficulties. No one, however, has heretofore succeeded in supplying that need. No device has heretofore been devised which could be manufactured and sold at low cost and which would overcome the aforementioned difficulties.

The object of the present invention is to provide a device which will adequately supply the above-mentioned need. The device provided by this invention is simple and inexpensive to construct, and therefore it may be sold at low cost. Moreover, it completely overcomes the aforementioned difficulties.

For the purpose of disclosure of the invention, there is shown in the accompanying drawing a single embodiment of the invention which, however, is capable of various forms of physical expression.

In the drawing:

Fig. 1 is a small-scale elevational view of the device with a paint can supported thereby;

Fig. 2 is a plan view of the same;

Fig. 3 is a view, on a relatively larger scale, partly in section and partly in elevation, showing the adaptability of the device for the supporting of different sized paint cans;

Fig. 4 is a sectional view taken along line 4—4 of Fig. 2; and

Fig. 5 is a perspective view of the can-retaining member which constitutes an element of the device.

Referring more particularly to the drawing, there is provided a supporting base 10, which is adapted to receive and support different sized paint cans and which is larger in area than the bottom of the largest can to be supported. As shown in Fig. 3, the base has a relatively deep recess 11 which is adapted to support a paint can of relatively small size, as represented by the dot-and-dash outline 12. The base also has a relatively shallow recess 13 which is adapted to receive a larger sized paint can represented by the dot-and-dash outline 14. It may be assumed,

2

by way of example, that the cans represented at 12 and 14 are pint and quart cans, respectively. The base 10 may be stamped from sheet metal, in which case the recesses 11 and 13 may be formed by stamping the base so as to provide a relatively deep circular portion 15 and a relatively shallow annular portion 16 surrounding the portion 15. It will be seen from the illustration of Fig. 3 that when the smaller sized can represented at 12 is used, it seats in the well formed by the deeper portion 15, and when the larger size can represented at 14 is used, it seats on the annular ledge provided by the shallower portion 16.

15 The base 10 also has an annular well 17 which surrounds the supported paint can and the purpose of which is to receive any overflow or spillage of the paint and thus prevent the paint from getting onto the supporting surface represented

20 at 18. Where the base is formed as a stamping, as above mentioned, it is a simple matter to form the annular well 17 therein during the stamping operation.

Secured to the base 10 is a vertical tubular handle 19 which is disposed in horizontally spaced relation to a supported can. The handle may be formed from simple metal tubing, and it may be secured to the base in any suitable manner, e. g. by welding, as indicated at 20. In the specific embodiment illustrated, the upper end of the

25 handle 19 is slotted as at 21 and is provided with threads 22 to receive an internally threaded collar 23 which preferably has its outer surface knurled. A member 24 has a stem or shank portion 25 which extends telescopically into the tubular handle 19 so as to be movable vertically relative thereto. The purpose of the slotted end of handle 19 and the associated collar 23 is to provide a tight frictional fit between the portion

30 25 of member 24 and the handle. The collar 23 serves to constrict the slotted portion of the handle tightly against the stem or shank 25 of member 24. Preferably two or more slots will be provided in the upper part of the handle 19 to give the desired constriction of the slotted portion and the consequent desired frictional engagement of the parts.

The primary purpose of member 24 is to engage the top of a supported can, such as shown at 26 in Fig. 1. To this end, the member 24 has a laterally extending portion 27 which is adapted to engage the top of the can. The portion 27 also serves as a brush support and it provides a brush-wiping edge. It also serves as a drip means to

55 convey any paint thereon back into the can. To

these ends, the said portion is widened, as clearly shown in Fig. 5, and it is slightly dished so as to constitute a sort of shallow trough. In the specific embodiment illustrated, the member 24 is formed of sheet metal, and the portion 27 has a central longitudinal bend 28 from which the opposite sides extend upward at a slight angle, and the side edges are turned up, as at 29 and 30. When the portion 27 is in engagement with the top of a can, it spans the top opening of the can, as shown in Figs. 1, 2 and 4, and it may be used to support a paint brush, such as shown at 31 in Figs. 1 and 2. Moreover, the edge 32, which extends across the top of the can, may be used as a wiping edge during the painting operation, and the paint thereon will run inward and will drip into the can. It will be apparent that the elements 10, 19 and 25 constitute means cooperable with a paint can for supporting the brush-rest member 27.

In using the device, it will be apparent that it is merely necessary to move the member 24 so as to permit the placing of the can in the proper recess of the supporting base 10 and then move said member into engagement with the top of the can. The paint can may be easily carried about from place to place merely by grasping the handle 19. There is no possibility of the paint can being knocked over since it is securely held in its seating recess by member 24. Moreover, the device effectively prevents spillage of paint onto the supporting surface, and it enables the user to perform the painting operation without getting paint on his hands.

It will be seen that the device is extremely simple in construction and it may be manufactured inexpensively and sold at low cost.

It will be apparent that a device constructed according to the invention and embodying the features thereof may vary widely as to its physical construction, and therefore the invention is by no means limited to the specific embodiment shown.

I claim:

1. A device for supporting a receptacle, such as a paint can, comprising a supporting base adapted to receive a receptacle and being larger in area than the bottom of the receptacle, said base having a well of sufficient size to surround the supported receptacle to receive any overflow or spillage of the receptacle contents, a handle secured to said base and extending vertically therefrom in horizontally spaced relation to the supported receptacle, and a member telescopically connected with said handle and having a laterally extending portion adapted to engage the top of said receptacle and hold it securely on the base, said receptacle-engaging portion being shaped to constitute a brush support and to provide a brush-wiping edge.

2. A device for supporting a receptacle, such as a paint can, comprising a supporting base having a plurality of recesses adapting the base to receive different sized receptacles, said base being larger in area than the bottom of the largest receptacle to be supported, said base having a well of sufficient size to surround the supported receptacle to receive any overflow or spillage of the receptacle contents, a handle secured to said base and extending vertically therefrom in horizontally spaced relation to the supported receptacle, and a member telescopically connected with said handle and having a laterally extending portion adapted to engage the top of said receptacle and hold it securely on the base, said

receptacle-engaging portion being shaped to constitute a brush support and to provide a brush-wiping edge.

3. A device for supporting a receptacle, such as a paint can, comprising a supporting base adapted to receive a receptacle and being larger in area than the bottom of the receptacle, a tubular handle secured to said base and extending vertically therefrom in spaced relation to the supported receptacle, and a member telescopically engaged with said handle for vertical movement and having a laterally extending portion adapted to engage the top of said receptacle and hold it securely on said base.

4. A device for supporting a receptacle, such as a paint can, comprising a supporting base having a plurality of recesses adapting the base to receive different sized receptacles, said base being larger in area than the bottom of the largest receptacle to be supported, a tubular handle secured to said base and extending vertically therefrom in spaced relation to the supported receptacle, and a member telescopically engaged with said handle for vertical movement having a laterally extending portion adapted to engage the top of said receptacle and hold it securely on said base, and means for locking said member in different positions of adjustment for receptacles of different heights.

5. A device for supporting a receptacle, such as a paint can, comprising a supporting base adapted to receive a receptacle and being larger in area than the bottom of the receptacle, said base having a well of sufficient size to surround the supported receptacle to receive any overflow or spillage of the receptacle contents, a tubular handle secured to said base and extending vertically therefrom in spaced relation to the supported receptacle, and a member telescopically engaged with said handle for vertical movement and having a laterally extending portion adapted to engage the top of said receptacle and hold it securely on said base.

6. A device for supporting a receptacle, such as a paint can, comprising a supporting base adapted to receive a receptacle and being larger in area than the bottom of the receptacle, a tubular handle secured to said base and extending vertically therefrom in horizontally spaced relation to the supported receptacle, and a member telescopically engaged with said handle for vertical movement and having a laterally extending portion adapted to engage the top of said receptacle and hold it securely on said base, said receptacle-engaging portion being shaped to constitute a brush support and to provide a brush-wiping edge.

7. A device for supporting a receptacle, such as a paint can, comprising a saucer-like supporting base on which a receptacle may be placed, said base being larger in area than the bottom of the receptacle, a vertical post-like handle extending upward from said base in spaced relation to the supported receptacle, and means telescopically engaged with said handle and engageable with the top of the supported receptacle to hold the receptacle firmly on said base.

8. A device for supporting a receptacle, such as a paint can, comprising a supporting base adapted to receive a receptacle and being larger in area than the bottom of the receptacle, means on said base to positively restrain the receptacle against lateral movement relative to the base, a member adapted to firmly engage the top of the supported receptacle, and telescopically inter-

engaged elements connected to said base and said member, respectively, for holding said member in engagement with the top of said receptacle, said member serving cooperatively with said restraining means to hold the receptacle positively in immovable relation to said base.

9. A device for supporting a receptacle, such as a paint can, comprising a supporting base adapted to receive a receptacle and being larger in area than the bottom of the receptacle, means on said base to positively restrain the receptacle against lateral movement relative to the base, a member adapted to firmly engage the top of the supported receptacle, and a tubular handle telescopically supporting said member and adapted to hold said member in fixed relation to the base, said member serving cooperatively with said restraining means to hold the receptacle positively in immovable relation to said base.

10. A device for supporting a receptacle, such as a paint can, comprising a supporting base adapted to receive a receptacle and being larger in area than the bottom of the receptacle, means on said base to positively restrain the receptacle against lateral movement relative to the base, a member adapted to firmly engage the top of the supported receptacle, a handle extending upward from said base in spaced relation to the supported receptacle and supporting said member

for vertical movement, and means for securely holding said member in a position for firm engagement with the top of the supported receptacle, said member serving cooperatively with said restraining means to hold the receptacle positively in immovable relation to said base.
